UNITED STATES PATENT OFFICE.

MATTS JACOB MUSTONEN, OF NEWBERRY, MICHIGAN.

FLYING-MACHINE.

1,130,623.

Specification of Letters Patent. Patented Mar. 2, 1915.

Application filed April 17, 1914. Serial No. 892,624.

To all whom it may concern:

Be it known that I, MATTS JACOB MUSTONEN, a citizen of the United States, residing at Newberry, in the county of Luce and State of Michigan, have invented new and useful Improvements in Flying-Machines, of which the following is a specification.

My invention relates to certain new and useful improvements in flying machines and its object is to provide a flying machine, in conjunction with other features, is designed to include a body partitioned to form one or more compartments capable of being exhausted of air or filled with gas lighter than air to secure the added buoying or lifting effect secured by the provision of a vacuum and consequent displacement of air weight or the use of a suitable buoying gas.

A further object of the invention is to provide a flying machine which is capable of travel upon the surface of a body of water and of being launched from and of alighting upon land or water; which is adapted to hover in the air over any given point, and of ascending or descending either in a direct vertical path or in an inclined plane and of being controlled in its vertical descent as desired; which is adapted to be ballasted for water travel in a novel and efficient manner; and which embodies features of construction giving great lifting capacity and speed, ease of control and general efficiency.

With the above and other objects in view, the invention consists of the features of construction, combination and arrangement of parts herein fully described and claimed, reference being had to the accompanying drawings in which:—

Figure 1 is a front elevation of a flying machine embodying my invention. Fig. 2 is a side elevation of the same. Fig. 3 is a top plan view of the machine. Fig. 4 is a vertical longitudinal section thereof. Fig. 5 is a vertical transverse section. Fig. 6 is a sectional plan view showing the drive gearing and controlling device. Fig. 7 is a fragmentary top plan view showing a modified propelling system. Fig. 8 is a view of the gearing thereof. Fig. 9 is a view showing a modified arrangement of lifting propellers. Fig. 10 is a side elevation showing a different form of body. Fig. 11 is a lon-

gitudinal section thereof. Fig. 12 is a transverse section thereof.

In carrying my invention into practice, I provide a body or car 1, preferably of streamline contour, which body or car is hollow throughout its length and constructed of a framework and sheathing of suitable materials possessing lightness, strength and durability. The car is preferably formed with a suitable hydroplane base or surface 2, adapting it to alight upon, travel on and rise from a body of water, and may also be provided with suitably cushioned launching and landing wheels 3 and skids 4, rendering it capable of being launched from and landed upon the ground in the usual manner. Carried by the body is a supporting surface 5, which may be of the monoplane, biplane or other suitable type, a biplane surface being shown in the present instance.

In accordance with my invention the interior of the hollow body or car 1 is subdivided by suitable partitions 6 to provide a compartment or cock pit 7 for occupancy by the aviator and passengers, if any, and within which are arranged the controlling devices, employed, said compartment also serving as an inclosure for a motor 8. The remainder of the body is divided by the said partitions into hermetically sealed chambers 9 and a bottom chamber or compartment 10. The car or body is designed to be rendered superbuoyant by either relieving the same of the weight of the air by exhausting air from the compartments 9 to form a vacuum therein, or by filling said compartments with hydrogen or other gas lighter than air, the air being exhausted or the gas introduced through suitable valved passages 11. The compartment 10 may, under ordinary conditions, also be exhausted of air or filled with a buoyant gas and is designed in practice to serve as a ballasting chamber, allowing the machine to be weighted as required in water travel, to regulate or vary the amount of water displaced thereby and the depth of submergence of the base of the car or body. To this end, the sides of the body are provided with apertures 12 governed by gates or doors 13 adjustably mounted for movement to positions to control said apertures for the admission of water or discharge of the same. Connections 14 couple said gates or doors

with an operating or controlling device 15 whereby the doors may be adjusted. For the purpose of discharging the water taken into the compartment 10 at any time, to 5 lighten the machine for aerial travel, I provide a pump 16 having one or more check valved outlets 17, and connected by a drive chain 18 with the shaft 19 of the motor 8, whereby said pump may be driven when 10 ever desired from the motor. The sprocket gear on the shaft 19 engaged by the chain 18 is loosely mounted on the shaft and adapted to be coupled thereto and uncoupled therefrom by means of a suitable clutch 20 15 adjustable by means of a control member 21, whereby the clutch may be thrown into and out of action.

The supporting surface 5 may be of any suitable area and lifting capacity and operates 20 in conjunction with the superbuoyant body 1 to give the machine a high degree of lifting and carrying capacity. For the purpose of driving the machine in straightaway flight, I provide upon the shaft 19 at the 25 tail end of the machine a driving propeller 22, and for the purpose of starting and stabilizing the machine I provide at the rear end of the body a horizontal rudder 23 and vertical rudder 24, coupled by suitable connections 30 to control devices 25 and 26 within the compartment 7, by which said rudders may be conveniently adjusted for starting and stabilizing actions.

Arranged at the sides of the car or body 35 1 are supporting brackets 27 in which are journaled vertical shafts 28 carrying lifting and stabilizing propellers 29, which, in the organization shown, are disposed between the superposed wings of the supporting surface 40 5. The shafts 28 are in gear with horizontal shafts 30 driven by chains 31 from the motor 8, the sprocket wheels on the shaft 19 around which the chains 31 pass are loosely mounted on said shaft and are adapted 45 to be coupled to and uncoupled from the shaft by the clutch devices 32 independently adjustable by control devices 33, by which the propellers 29 may be simultaneously independently thrown into or out of action 50 for lifting and stabilizing operations. It will be evident that the propellers 29 may be employed in operation to lift the machine directly from the ground or water into the air, or employed in conjunction with the 55 propeller 22 to launch the machine in the ordinary way, in which action the lifting motion of the propellers 29 reduce to a material degree the length of running start required for the launching motion, and it will 60 be also understood that by means of these propellers the machine may be supported and caused to hover in the air over any given point or allowed to descend slowly in a straight vertical path, the machine thus being 65 adapted to ascend or descend directly or

in an inclined plane, as desired. By also operating the propellers 29 independently, the said propellers may be employed as lateral balancing devices in an obvious manner.

It will be evident from the foregoing description that the invention provides a flying machine which is capable of being launched and controlled, in a much more ready, convenient and efficient manner than the machines of ordinary construction in common use, and that it embodies novel and improved means for increasing its lifting capacity as well as its efficiency in water operations and launching and alighting actions. Furthermore, it will be evident that the invention provides a machine which may be made structurally heavier and stronger than ordinary machines, or which with the same weight and aerial surfaces will have greater lifting capacity than machines of the ordinary type, since the superbuoyant body increases the buoyancy and flotation capacity of the machine. In some cases, I may provide a pair of rear driving propellers 34 arranged on opposite sides of the longitudinal center of the body and driven by chains 35 or other suitable gearing from the motor shaft 19, as shown in Figs. 7, 8 and 9, and as also shown in these views I may provide a second or auxiliary set of lifting and stabilizing propellers 36 arranged in spaced relation to the lifting and stabilizing propellers 29, in which event the two sets of propellers 29 and 36 will be properly disposed at the sides of the body for efficient action. The construction of the body or car may also be varied, as shown in Figs. 10, 11 and 12, in which I have shown a car 37 which is substantially cigar-shaped or of a 105 shape conforming approximately to the bodies of air and the shapes of the dirigible balloon type. In this case the body 37 may have the pilot's compartment 38 arranged wholly on the interior thereof and reach 110 from the exterior through a door or passage 39, and the sides of said compartment may be provided with suitable port holes 40 and the front with observation openings 41 allowing the pilot to see ahead. These and 115 other like modifications are held to fall within the spirit and scope of my invention.

I claim:

1. A flying machine including a body having a supporting and suitable steering gear, 120 said body being partitioned to provide a pilot's compartment, buoying compartments and a bottom ballasting compartment, a motor within the body, propelling means driven thereby, a pump for exhausting water from the ballasting compartment, means for driving said pump from the motor, lifting and stabilizing propellers, and means for driving the same from the motor.

2. A flying machine including a body hav- 130

ing a supporting surface and suitable steering gear, said body being partitioned to provide a pilot's compartment, buoying compartments having valved passages and a bottom ballasting compartment having inlet and exit apertures, gates controlling said apertures, and operating means for opening and closing the gates, a motor within the body, propelling means driven thereby, a pump for exhausting water from the bal-

lasting compartment, means for driving said pump from the motor, lifting and stabilizing propellers, and means for driving the same from the motor.

In testimony whereof I affix my signature in presence of two witnesses.

MATTS JACOB MUSTONEN.
